CARRYING BAG FOR LAUNDRY AND THE LIKE

James Christie, La Puente, Calif.
(5656 Cedarglen Drive, Azusa, Calif. 91702)

Filed Aug. 24, 1967, Ser. No. 8,373

Term of patent 14 years

Int. Cl. D7—06

U.S. Cl. D49—8.1

FIG. 1.

FIG. 2.

FIGURE 1 is an elevational view of a carrying bag for laundry and the like, showing my new design, the opposite side being a mirror image of the side shown; and

I claim:

The ornamental design for a carrying bag for laundry and the like, as shown and described.
